UNITED STATES PATENT OFFICE

CHARLES H. LANE AND CHARLES H. REYNOLDS, OF HOUSTON, TEXAS

WHIP STOCK

Application filed August 5, 1929. Serial No. 383,539.

This invention relates to new and useful improvements in a whip stock.

One object of the invention is to provide a whip stock of the character described with 5 novel means, operable by fluid pressure, and effective to anchor the whip stock against downward movement in, and against rotative movement relative to, a pipe in a well bore in which the whip stock is located.

10 In drilling a well, a casing is often set in the well bore and it sometimes becomes necessary to perforate the side of the casing to form an opening through which the drilling tool may pass in order to side track the lower 15 end of the original bore. In the work of perforating the casing a whip stock is located in the casing having a sloping face and a milling tool is then let down into the casing and is forced by said sloping face against the 20 side of the casing to be perforated and this milling tool eventually cuts through and perforates said casing to provide an opening through which the drilling tool and the drill stem driving the same, may work.

25 It has been a common practice to attach the whip stock to the upper end of a string of pipe of the desired length and then to lower this assembly into the bore with said string of pipe resting on the bottom of the bore and 30 serving to support the whip stock at the desired place in the casing. However when a whip stock is so set it is liable to turn or revolve about in the casing and thus seriously interfere with the work of milling through 35 the casing. It is the prime object of this invention to provide a whip stock that may be readily located at any desired place in the casing and then securely anchored against rotative movement in the casing.

40 With the above and other objects in view the invention has particular relation to certain novel features of construction, operation and arrangement of parts, an example of 45 which is given in this specification and illustrated in the accompanying drawings wherein:

Figure 1 shows a side elevation of a whip stock anchored in a casing and shown partly in the casing, and

50 Figure 2 shows a transverse sectional view

thereof taken on the line 2-2 of Figure 1.

Referring now more particularly to the drawings wherein like numerals of reference designate similar parts in each of the figures, the numeral 1 designates the whip stock proper, of a general cylindrical contour but whose upper end has a sloping face 2 which is concaved, said sloping face extending up to the upper end of the whip stock. Beneath the cylindrical body 1 the whip stock is reduced forming a downwardly tapering mandrel 3 preferably triangular in cross sectional contour thus presenting the flat downwardly converging faces 4. These faces have the vertical dovetailed grooves or guides 5 therein, and the bottom of each groove is formed with the upwardly pitched ratchet teeth as 6. Slidable on the faces 4 are the respective slip jaws 7 which have dovetailed tenon 8 which move in the corresponding grooves 5. These tenons have the downwardly pitched ratchet teeth 9 adapted to cooperate with and engage the corresponding teeth 6.

Attached to the lower end of the mandrel there is a cylinder 10 in which there is a piston 11. Connecting rods 12 are provided whose lower ends rest on the piston 11 and their upper ends may rest against, or be pivoted to, the corresponding slip jaws 7. These connecting rods work through upwardly diverging bearings provided in the cylinder 10 and in the lower end of the mandrel 3 and may be made sectional if desired, so that they may be more readily inserted into said bearings, in assembling them. There is an axial channel 13 leading down through the whip stock proper and through the mandrel and wall of the cylinder and whose lower end enters said cylinder beneath the piston. The cylinder 10, as shown, is screwed onto the reduced lower end of the mandrel 3 and these connected parts have annular grooves which register, when the parts are screwed together forming a channel 13' which forms a part of the passageway 13 and which is provided so that when the parts are secured together, said channel will not be blocked, thus dispensing with the necessity of exactness in screwing the cylinder on the mandrel. Above said piston the cylinder has an inlet port 14.

The upper end of the channel 13 is enlarged and provided with left hand threads 15.

In operation the whip stock may be assembled as shown and attached to the lower end of a drill stem or other string of pipe, said lower end of said string having left hand threads which are screwed into the upper end of the channel 13.

When the device is let down into the casing

- 10 16 in the bore to the desired place, fluid under pressure may then be forced down through said string and through the channel 13 into the cylinder 10 beneath the piston 11 and said piston will be thereby forced upwardly forcing the slip jaws 7 upwardly and outwardly along the faces 4 into engagement with the casing and the teeth 6, 9 will interengage to maintain said slip jaws in such engaging position. It is to be
- 15 20 noted that two of said jaws have external circumferential teeth which will serve to engage the casing and anchor the whip stock against downward movement and another of said slip jaws has external vertical teeth 25 which will engage the casing to hold the whip stock against rotative movement.

When the whip stock is set the setting stem or string may be detached from it by turning said string to the right and then withdrawn and a milling tool attached to the lower end of an operating string may then be let down into the casing and rotated and said tool will be deflected by the face 2 against the opposing side of the casing to be perforated and 35 said milling tool will thereby cut the required opening through the side of the casing 16 through which drilling operations may be thereafter carried on.

A preferred form of the invention has 40 been disclosed in the drawings and specifications by way of illustration only while the broad principle of the invention will be defined by the appended claims.

What we claim is:

- 45 1. A whip stock having a deflecting face and a depending mandrel having downwardly converging faces, slip jaws movable on said faces, a cylinder attached to the mandrel, a piston in said cylinder, connecting 50 rods connecting said jaws to said piston, said whip stock having a channel leading from the upper end thereof and entering the cylinder beneath said piston.

2. A whip stock including a deflector 55 whose upper end is formed with a sloping face, and anchoring means for the deflector comprising outwardly movable slip jaws, a cylinder, a piston therein, operative connections between said piston and jaws, there being a channel entering said cylinder on one 80 side of the piston through which fluid, under pressure, may be utilized to move said piston to effect said outward movement of said jaws.

- 3. A whip stock adapted to be located in

a surrounding well casing and having a sloping upper end face and having a face which converges downwardly toward the axial central line of said whip stock, a slip jaw movable on said downwardly converging face, a cylinder, a piston therein, an operative connection between said piston and jaw, there being a channel entering said cylinder on one side of the piston through which fluid under pressure may be forced to move the piston to effect the upward and outward movement of the jaw into engagement with said casing.

4. A whip stock adapted to be located in a well casing and including a deflector having a sloping upper end face, and supporting and anchoring means for the deflector comprising casing engaging means movable into active positive into engagement with said casing, and means operable by fluid under pressure and connected to said engaging means and effective to move the same into such active position to anchor the whip stock in said casing.

5. A whip stock adapted to be located in a casing in a well including a body having a tapering upper end face, slip jaws movable outwardly into active position in engagement with the casing, means operable by fluid under pressure and connected to said jaws and effective to move the same outwardly into engagement with the casing, said whip stock having a channel through which fluid, under pressure, may be applied to said jaw moving means to operate the same.

6. A whip stock adapted to be located in a well casing and having a tapering upper end face, and a mandrel having converging faces, slip jaws on the mandrel faces movable outwardly thereon into engagement with said casing, means operable by fluid, under pressure, and connected to said jaws and effective to move them outwardly into such engagement.

7. A whip stock adapted to be located in a well casing and having a tapering upper end face, and a mandrel having converging faces, slip jaws on the mandrel faces movable outwardly thereon into engagement with said casing, means operable by fluid, under pressure, and connected to said jaws and effective to move them outwardly into such engagement, some of said jaws having teeth which engage the casing to prevent the downward movement of the whip stock and other of said jaws having teeth which engage the casing to prevent the rotative movement of said whip stock.

8. A whip stock to be located in a casing in a well and having a sloping upper end face, and having casing engaging jaws movable outwardly into engagement with said casing, means operable by fluid, under pressure, and connected to said jaws and effective to move them outwardly, some of said jaws having teeth which anchor the whip

stock against downward movement in the casing, other of said jaws having teeth which anchor said whip stock against rotation in the casing.

5 9. A whip stock adapted to be located in a well casing and having a deflector and means operable by fluid pressure into engagement with the casing and effective to anchor the deflector in the casing.

10 10. A whipstock adapted to be lowered into a pipe in a well bore and having means operable by fluid pressure for anchoring the whip stock in the pipe.

15 In testimony whereof we have signed our names to this specification.
